UNITED STATES PATENT OFFICE.

RUTHERFORD BOYD, OF LEONIA, NEW JERSEY; FERDINAND W. NITARDY, OF BROOKLYN, AND JAMES C. LEWIS, OF FOREST HILLS, NEW YORK, ASSIGNORS TO E. R. SQUIBB & SONS, OF NEW YORK, N. Y., A CORPORATION OF NEW YORK.

DESIGN FOR A BOTTLE.

Application filed November 13, 1926. Serial No. 19,724. Term of patent 14 years.

To all whom it may concern:

Be it known that we, RUTHERFORD BOYD, residing at and whose post-office address is 115 Prospect Street, Leonia, county of Bergen, and State of New Jersey; FERDINAND W. NITARDY, residing at and whose post-office address is 29 Monroe Place, Brooklyn, county of Kings, and State of New York; and JAMES C. LEWIS, residing at and whose post-office address is Forest Hills, county of Queens, and State of New York, citizens of the United States, have invented a new, original, and ornamental Design for a Bottle, of which the following is a specification, reference being had to the accompanying drawing, forming part thereof.

We claim:

The ornamental design for a bottle, as shown.

RUTHERFORD BOYD,
FERDINAND W. NITARDY,
JAMES C. LEWIS.
